ICE SHAVER

Clement C. Clawson, Jr., Flagtown, N. J., assignor
to The Clawson Machine Co., Inc., Flagtown,
N. J., a corporation of New Jersey

Application September 30, 1930, Serial No. 485,362

2 Claims. (Cl. 83—62)

This invention relates, generally, to apparatus for cutting or shaving blocks of ice into flakes or crystals suitable for use in making snow balls and similar confections, and the invention has 5 reference, more particularly, to a novel ice shaver having a relatively great output capacity.

Ice shaving machines as heretofore commonly constructed have a pair of knives or blades, both of which knives sweep over the same cutting area. This form of construction generally results in one of the two knives doing substantially all of the cutting in use, while the other knife merely follows around and at times takes a slight cut or shaving. This condition is aggravated if 10 the depth settings of the two knives are not exactly the same. This type of machine has but a limited output, and the product produced is frequently of an ununiform or heterogeneous nature, rendering the same less desirable for major 15 uses.

The principal object of the present invention is to provide a novel ice shaver having a relatively large output capacity and employing an improved cutting unit comprising three cutting knives or 20 blades arranged in Y formation and being so constructed and disposed, that each knife sweeps over an independent cutting area, whereby each knife is caused to produce a maximum cutting effect and will cut at all times to the depth for 25 which it is set regardless of the depth setting of the other cutting knives.

Another object of the present invention lies in the provision of a novel ice shaver which is easily adaptable for use as a table machine as when discharging into a small container, or for use as a 30 machine having independent legs as when discharging into a large container set on the floor.

Other objects of this invention, not at this time more particularly enumerated, will be clearly understood from the following detailed description of the same.

The invention is clearly illustrated in the accompanying drawings, in which:—

Fig. 1 is a view in elevation of the novel ice shaver of this invention provided with removable legs, the plunger of the ice shaver being in its inner position within the shaver casing;

Fig. 2 is a fragmentary view looking at the left side of the structure shown in Fig. 1;

Fig. 3 is an enlarged plan view of the ice shaver with the plunger shown in its outer position;

Fig. 4 is an enlarged vertical sectional view with parts broken away of the ice shaver of this invention, the same being illustrated in the process 55 of shaving ice;

Fig. 5 is an enlarged fragmentary sectional view taken along line 5—5 of Fig. 4;

Fig. 6 is a view in side elevation of the cutting unit of Fig. 5; and

Fig. 7 shows the cutting knives or blades in 5 perspective.

Similar characters of reference are employed in the above described views, to indicate corresponding parts.

Referring now to the said drawings, the reference numeral 1 designates the novel ice shaver of this invention as a whole. The ice shaver 1 comprises a casing 2 provided with an opening 3 at its top for receiving ice blocks to be shaved or reduced to crystal shavings within the machine, 10 which crystal shavings are discharged through a mouth 7 provided at the bottom of casing 2. Casing 2 is provided with a depending standard 4 which serves to support the casing upon a base 5. Standard 4 is removably secured to the base 5 15 as by screws 6. Base 5 underlies the casing 2 and has a depression 8 formed in its upper surface for receiving a pan or tray such as 9, which is adapted to collect the crystal ice shavings 10 discharged from the mouth 7 of the machine. 20

A cutting unit comprising a disk shape cutter head 11 is disposed vertically within the lower portion of the casing 2 and adjacent the mouth 7. Cutter head 11 is provided with a hub 12 which is secured as by pin 13 to the inner end portion 25 of a shaft 14. Shaft 14 extends through and is rotatably mounted within a bearing 15 provided in casing 2 and has its outer end portion secured to a hand wheel 16, which hand wheel is illustrated as having a crank handle 17. The turning of hand wheel 16, as by manual operation of crank handle 17 causes the rotation of the cutting unit including cutter head 11. 30

Cutter head 11 is formed with three radial slots 18, 19 and 20 disposed in Y formation about the disk portion of this cutter head. These slots meet or merge into one another at the center of the cutter head adjacent the inner end of hub 12 and are spaced angularly 120 degrees from one another. The slots 18, 19 and 20 extend obliquely through the disk portion of the cutter head, thereby providing discharge apertures in the cutter head through which ice shavings, formed at the inner face of the cutter head, may move freely on their way to the discharge mouth 7. 40

The following or rearward wall of each of the slots 18 to 20, (i. e. with respect to the direction of rotation of the cutter head), makes an acute angle with the adjoining sector of the working face 28 of the cutter head and is formed wider 45 50 55

than the forward or leading wall of the slot to provide a knife or blade seat 21. To form the blade seat 21 the cutter head is illustrated as provided with radial ribs 40 adjacent slots 18 to 20.

5 The knife or blade seat 21 provided on the rearward wall of slot 18 supports a knife or blade 22 having a cutting portion 23 extending from the periphery of the cutter head radially inward for substantially one-third of the radius of the cutter head. The cutting portion 23 in use is adapted to sweep over an annular area bounded by circumferential lines, the larger of which has a radius equal to that of the cutter head and the smaller of which has a radius equal to substantially two-thirds of the radius of the cutter head. Cutting portion 23 of knife 22 thus does the cutting of the outer third of the radius of the cutter head, so that knife 22 may be termed the outer knife.

10 The knife or blade seat 21 provided on the wall of slot 19 supports a knife or blade 24 having a cutting portion 25 of a length equal to substantially one-third of the radius of the cutter head, which cutting portion extends over the middle third of the radius of the cutter head, as especially shown in Fig. 5. This cutting portion 25 is adapted in use to sweep over an annular area bounded by circumferential lines, the larger of which has a radius substantially equal to two-thirds of the cutter head radius, and the smaller of which has a radius equal to substantially one-third of the cutter head radius. The length of the cutting portion 25 is illustrated in the drawings and is preferably made somewhat greater than one-third of the radius of the cutter head so that the same will overlap slightly the inner marginal portion of the area passed over by the cutting portion 23 of blade 22. This overlapping is desirable in order to insure the complete cutting over of the area represented by the adjoining marginal portions of the middle third and outer third of the cutter head radius. This overlapping will be made evident by an observation of Fig. 5, wherein the dot and dash circumferential line extending between the cutting portion 23 and cutting portion 25 indicates such overlapping.

15 The knife or blade seat 21 provided on the wall of slot 20 supports a knife or blade 26 having a cutting portion 27 extending over the inner one-third of the radius of the cutter head. The cutting portion 27 is preferably slightly longer than one-third of the cutter head radius so that its cutting area will slightly overlap that of the cutting portion 25, thereby also insuring a complete cutting of ice swept over by the outer end of cutting portion 27 and the inner end of cutting portion 25. It will thus be noted, with the exception of a slight overlapping, that the outer knife 22, the middle knife 24 and the inner knife 26 will sweep over independent cutting areas in use, each of these knives serving to cut ice lying along one-third of the radius of the cutter head.

20 The knives 22, 24 and 26 are each provided with a pair of spaced, transversely elongated apertures 29, through which screws 30 extend to secure the knives to their respective seats 21. The screws 30 are threaded into the cutter head and preferably have washers 31 underlying their heads, to thereby obtain a better grip upon the knives. The elongated nature of apertures 29 permits the cutting blades 22, 24 and 26 to be varied so that the cutting depth may be altered as desired. Thus, to increase the cutting depths of the blades, it is merely necessary to loosen

25 screws 30 and move the blades so that the knife edges of the cutting portions 23, 25 and 27 are positioned further from the working face 28 of the cutter head. The working face 28 is divided into three sectors by the slots 18 to 20 and each of these sectors is cut away on small arcs 32 adjacent the center of the cutter head, to enable a more ready flow of ice shavings through slots 18, 19 and 20. The cutter head together with the knives 22, 24 and 26 mounted thereon provide a 10 cutting unit which in practice shaves ice with great rapidity.

30 The ice shaver is provided with a plunger 33 having a shank 34 formed thereon, which shank terminates in a yoke 35 that has its legs pivotally mounted upon the casing 2 as by bolts 36. Shank 34 is formed to provide a tapered aperture 37 for receiving a plunger handle 38 to be used in operating the plunger 33. A rubber stop 39 is provided upon the plunger handle 38 for cushioning 20 the movement of this handle when the same strikes the rim of casing 2, as especially illustrated in Fig. 1. Plunger 33 is provided on its inner surface with an arcuate, inwardly directed flange 42 which cooperates with the inner wall of casing 2 to guide the ice blocks 43 onto the working face 28 of the cutter head as the plunger is moved inwardly of the casing 2. The inner surface of plunger 33 is also provided with a plurality of pointed prongs 44 which grip the ice and aid in 35 directing the same toward the working face 28 of the cutter head.

35 The ice shaver is illustrated in Figs. 1 and 2 as provided with removable legs 45 which are secured at their upper ends to the casing 2 by 40 screws 46. With the legs 45 attached to the casing 2, the machine may be used as illustrated in Fig. 1, wherein the pan 9 is employed for collecting the ice shavings, or, if the base 5 is removed from casing 2, a larger container, such as a barrel, 45 may be placed below the casing 2 for collecting the ice shavings discharged from the machine. If the legs 45 are removed from the casing 2, the machine may be placed upon a table or other support for use, as illustrated in Fig. 4.

40 In operation, to put ice into the machine, the plunger handle 38 is turned outwardly so that the plunger 33 moves to its outermost position shown in Fig. 3. Blocks of ice 43 are then inserted through opening 3 of the casing 2 and allowed to collect in the bottom of the casing. The plunger is now moved inwardly of the casing 2, causing the inner surface thereof to contact with and grip the ice blocks 43 and to press these blocks toward the working face 28 of the cutter head. The operator now turns the hand wheel 16 to cause the cutter unit to revolve in the direction of the arrows indicated in Figs. 4, 5 and 6, thereby causing the cutting portions 23, 25 and 27 of the outer, middle and inner knives to cut the ice pressed against the working face 28. The cutter depth at which the knives are set will determine the size of the ice shavings produced, which shavings after being cut from the ice blocks fall through the slots 18 to 20 and through 65 mouth 7 into the pan 9. Since the interior wall of opening 3 conforms closely to the lower peripheral portion of the cutter head, as especially illustrated in Fig. 5, there is no possibility of unshaved ice passing through mouth 7.

60 Owing to the Y arrangement of the cutting knives 22, 24 and 26, there is a three point engagement between the cutting portions of these knives and the ice acted upon, which results in a substantial balancing of the forces acting upon the 70 75

cutter head and facilitates the manual operating of the machine with a minimum of effort. The use of three knives, each having cutting portions sweeping over independent cutting areas results in each one of these cutting portions operating at a maximum efficiency to effect a full depth of cut as measured by the extent of projection of the respective cutting portion beyond the working face 28 of the cutter head. Thus, each cutting portion in sweeping over its independent area is unaffected by the action of the remaining cutting portions, so that uniform ice shavings are obtained.

Each of the knives will cut at all times to the depth determined by the setting of the knife, regardless of the depth setting of the other two knives. If it is desired to produce a variety of ice shavings or ice shavings of varying thickness, the respective knives may be set at varying cutting depths. In use, it is found that the novel ice shaver of this invention has a greatly increased capacity over the old type of ice shavers, wherein the cutting blades swept over common cutting areas and wherein constant interference of one knife blade with another resulted in one blade doing practically all of the cutting, whereas the remaining blade or blades merely followed along without exerting any cutting action, but nevertheless tending to throw the ice away from the cutting edge of the working blade, thereby reducing the output of the machine.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

40 What is claimed is:—

1. In an ice shaver, a cutting unit comprising a cutter head having a forward circular working face, said cutter head being provided with three relatively wide radial slots therein disposed in 45 Y formation, the point of juncture of said slots being at the center of said working face, said cutter head being cut away along small arcs adjoining the point of juncture of said slots in order to facilitate the flow of ice shavings through said 50 radial slots, three knife blades, each of said knife blades being adjustably attached to a wall of a respective one of said radial slots, each of said

knife blades having a cutting portion of a length equal to one-third of the length of one of said slots, said cutting portion being positioned at a distance radially from the center of said cutter head that is unequal to the radial distances of the remaining cutting portions from the center of said cutter head, whereby the cutting portions of each of said knives sweeps over an annular cutting area in use that is different from the annular cutting areas of the remaining cutting portions, so that the ice shavings produced by each cutting portion are of uniform quality owing to the independent cutting action of each cutting portion.

2. An ice shaver comprising a casing having an ice receiving aperture at its top and an ice shaving discharge mouth at its bottom, a rotary cutting unit positioned within said casing adjacent said discharge mouth for shaving ice deposited within said casing and for passing the shavings to said discharge mouth, said cutting unit being of disc shape and having three radial slots arranged in Y formation therein, each of said slots having a knife mounted on the side wall thereof, said cutting unit being cut away along small arcs adjoining the juncture of said slots in order to facilitate the flow of ice shavings through said radial slots, said knives having cutting portions projecting forwardly of the front face of said cutting unit, the cutting portion of each of said knives having a length substantially equal to one-third of the length of one of said slots and being disposed at a radial distance from the center of said cutting unit that is unequal to the radial distances of the remaining cutting portions, whereby each of said cutting portions sweeps over an independent annular cutting area in use, a plunger pivotally mounted at the upper portion of said casing, and a handle secured to said plunger for use in moving said plunger into said casing for pressing ice toward said cutting unit, said plunger having pointed projections and an arcuate flange on the inner surface thereof for gripping the ice and for cooperating with the wall of said casing to urge ice into operative engagement with the knives of said cutting unit, said arcuate flange and the wall of said casing conforming to the perimeter of the said cutting unit, thereby preventing the discharge of unshaved ice from said ice shaver.

CLEMENT C. CLAWSON, JR.
